UNITED STATES PATENT OFFICE

HYMAN R. SEGAL, OF NEW YORK, N. Y., ASSIGNOR TO SEGAL FOUNDERS CORPORATION,
A CORPORATION OF NEW YORK

RAZOR

Application filed June 4, 1931. Serial No. 541,963.

This invention relates to a functionally and structurally improved razor. It is an object of the invention to provide a device of this character which will be of unitary and improved construction and by means of which a blade may be readily adjusted to give exactly the desired degree and angle of contact with the surface being shaved.

A further object of the invention is that of providing a razor the parts of which may readily be shifted from operative to inoperative position permitting of a rapid detachment and mounting of a blade and a proper cleansing of the razor or holder parts.

An additional object is that of furnishing a razor or blade holder embodying relatively few parts, each individually simple and rugged in construction and capable of manufacture by automatic machinery, these parts being readily assembled to provide a compact apparatus operating over long periods of time with freedom from mechanical difficulties and which additionally may be sold at a relatively nominal figure.

With these and other objects in mind, reference is had to the attached sheet of drawings illustrating one practical embodiment of the invention and in which:

Fig. 1 is a partly sectional side elevation of a razor;

Fig. 2 is a similar view by showing the parts in extended or inoperative condition;

Fig. 3 shows the clamping plate and stem therefor;

Fig. 4 illustrates the tube and guard structure;

Fig. 5 is a side view of the guiding pin or member, and

Fig. 6 is a perspective view of the shifting element.

In these views, the numeral 10 indicates a guard which may be provided with comb portions and which preferably has upon its upper face a blade positioning abutment 11. The edges of this abutment are preferably inclined as at 12 for cooperation with the ends of a clamping plate 13 pivotally mounted as at 14 by a stem 15. The guard is formed with an opening in line with a tube 16 which

mounts the guard and the bore of this tube slidably accommodates the stem 15.

Slidably encircling the tube is a sleeve 17. Mounted on the sleeve is a shifting member as shown in Fig. 6. This member preferably includes flat upper and lower surfaces 18 riding within a groove 19 formed in the lower end of the stem. The member may additionally include a collar 20 which extends through a slot 21 formed in the tube and which is threaded to receive a screw 22 which prevents movement of the member with respect to the sleeve.

The tube 16 may additionally be formed with an opening 23, the edges of which hold the screw threaded head 24 of a pin 25. The body of the latter extends into the bore of the tube and into a groove 26 formed in the stem. As will be noted, this groove is preferably formed with a tangentially offset end 27 and in traversing this portion of the groove, the pin will obviously serve to effect a relative turning of the stem and tube.

As afore brought out, clamping plate 13 is preferably mounted on a pivot 14 so as to be capable of swinging movements with respect to the stem. To induce such movements, one end of the plate is preferably weighted. Thus, with the parts assembled in the manner shown in Fig. 1, it will be appreciated that if the sleeve 17 is moved upwardly along the tube, this will result in the actuating member shown in Fig. 6 being likewise moved. Due to the connection of the latter with the stem, the stem will also be shifted to elevate the clamping plate from the guard. During this shifting rotation of the stem will be prevented due to the fact that the pin 25 is traversing the straight portion 26 of the groove. However, under continued shifting, the pin will traverse the tangential portion 27 thus causing a turning of the stem and a corresponding movement on the part of the clamping plate. As the latter becomes elevated, it is obvious that it will rock and during the final stages of such elevation, the turning results which causes the clamping plate to finally assume a position with respect to the guard such as has been shown in Fig. 2. The parts are now in posi-

tion to receive a razor blade or to permit of the application thereof to the guard. The blade, while not shown, may simply be of the flexible double edge type and with an opening such that (a) the clamping plate 5 may be passed therethrough; and (b) the positioning lug or abutment 11 may be disposed therein accurately to retain and support the blade.

Upon the sleeve being moved downwardly over the tube, it is obvious that the stem will be correspondingly shifted and the edge of the clamping plate will engage for example one of the cam surfaces 12 of the abutment so that a tilting of the plate will be initiated. Thereafter, the end of the plate will guide over the upper surface of the blade or—the corresponding surface of the guard—to finally assume the position shown in Fig. 1.

Now, with a view to providing means which will serve to lock the parts against accidental movement and also to permit of an accurate adjustment of blade tension and disposition of the blade, it will be noted, as shown in Fig. 3, that the end of the stem may be extended and threaded as at 28. Rotatably mounted by the lower end of the tube is a knob 29 which has a threaded bore capable of accommodating the extension 28. Consequently, after the sleeve has been shifted to its downward position, a rotation of the knob will cause a final shifting and adjustment of the stem and clamping plate which will, in turn, result in the desired adjustment of the blade. Thus, among others, the several objects of the invention as specifically afore noted, are achieved. Obviously, numerous changes in construction and arrangement of the parts might be resorted to without departing from the spirit of the invention as defined by the claims.

Having described my invention, what I claim as new and desire to secure by Letters Patent is:

45 1. A razor including a guard, a clamping plate, a stem mounted on the latter, a tube mounted on said guard said stem being formed with a groove having an offset end portion, means extending from said tube into said groove to guide said stem in its movements with respect to said tube, a sleeve slidably encircling said tube, said tube being formed with a slot and an actuating member connected to said sleeve and extending 50 through said slot to engage said stem whereby the latter will shift in response to shifting of said sleeve along said tube.

2. A razor including a guard, a tube mounted on the same and formed with a slot, a clamping plate, a stem pivotally supporting said clamping plate and slidably disposed within said tube, a sleeve enclosing said tube, means secured to said sleeve and extending through said tube slot to engage said stem to shift the latter with respect to

said tube, said stem being formed with a tangentially extending groove, and means extending from said tube into said groove to guide said stem.

3. A razor including a guard, a tube 70 mounted on the same and formed with a slot, a clamping plate, a stem pivotally supporting said clamping plate, and slidably disposed within said tube, a sleeve enclosing said tube, means secured to said sleeve and 75 extending through said tube slot to engage said stem to shift the latter with respect to said tube, said stem being formed with a tangentially extending groove, means extending from said tube into said groove to 80 guide said stem, and means associated with said stem and tube respectively to lock such parts against movement.

4. A razor including a guard, a tube 85 mounted on the same, a stem movably disposed within said tube, a clamping plate for cooperation with said guard and pivotally mounted on said stem, said stem being formed with a groove extending substantially longitudinally of its body, said stem being formed with a further and circumferentially extending groove, means extending from said tube into said first-named groove to 90 guide said stem as the latter moves with respect to said tube, and means extending into said last-named groove for shifting said stem with respect to said tube.

5. A razor including a guard, a tube mounted on the same, a stem movably disposed within said tube, a clamping plate for cooperation with said guard and pivotally mounted on said stem, said stem being formed with a groove extending substantially longitudinally of its body, said stem being formed with a further and circumferentially extending groove, means extending from said tube into said first-named groove to guide said stem as the latter moves with respect to said tube, a sleeve slidably encircling said tube, said tube being formed with a slot, and means extending from said tube through 110 said slot into said last-named stem groove to effect shifting of said stem with respect to said tube.

6. A razor including, in combination, a 115 tube formed with a longitudinally extending slot, a guard mounted on said tube, a rod slidable within said tube, a clamping plate pivotally mounted on said rod, said rod being formed with an annular groove 120 adjacent its lower end, a sleeve encircling said tube and slidable along the longitudinal axis thereof, and means carried by said sleeve and passing through the longitudinal slot in said tube to engage the annular groove in said rod whereby said sleeve and rod will move together.

7. A razor including, in combination, a tube formed with a longitudinally extending slot, a guard mounted on said tube, a rod

slidable within said tube, a clamping plate pivotally mounted on said rod, said rod being formed with an annular groove adjacent its lower end, a sleeve encircling said tube and slidable along the longitudinal axis thereof, a non-circular member cooperating with the annular groove in said rod and formed with a screw-threaded opening and a screw adapted to pass through the longitudinal slot in said tube and effect a coupling of said sleeve and rod whereby these members move together.

In testimony whereof I affix my signature.
